UNITED STATES PATENT OFFICE.

EDWARD F. CREEVY, OF CHICAGO, ILLINOIS.

AUTOMATIC-FEED MEMORANDUM DEVICE.

1,400,029.

Specification of Letters Patent.

Patented Dec. 13, 1921.

Application filed November 13, 1920. Serial No. 423,790.

To all whom it may concern:

Be it known that I, EDWARD F. CREEVY, a citizen of the United States, and a resident of the city of Chicago, in the county 5 of Cook and State of Illinois, have invented certain new and useful Improvements in an Automatic-Feed Memorandum Device; and I do hereby declare that the following is a full, clear, and exact description of the 10 same, reference being had to the accompanying drawings, and to the numerals of reference marked thereon, which form a part of this specification.

This invention relates more particularly 15 to an improved form of an automatic feed memorandum device wherein paper is advanced over a pivoted writing table when said table is released from a depressed writing position.

It is an object of this invention to construct a memorandum device with an automatic paper feed.

It is also an object of this invention to provide a memorandum device having a pivoted writing table adapted to be pressed down into a writing position and further adapted upon release thereof to automatically return to normal position and simultaneously advance paper over the writing 25 table.

Another object of the invention is the construction of a memorandum device wherein a movable writing support is adapted to automatically feed paper into a 30 position to be written on.

It is a further object of the invention to construct a memorandum holder adapted to automatically feed paper at the completion of the writing of each line of a 35 memorandum being written thereon.

It is furthermore an object of this invention to provide a memorandum device wherein the resting of a hand upon a table will move the same into a position to permit writing thereon, said table adapted upon removal of the hand at the completion of the writing of a line to return to normal position and automatically feed sufficient paper into the writing space to 40 permit writing of another line.

Another object of the invention is the construction of a memorandum device adapted to automatically and simultaneously feed both a primary paper and a secondary paper 45 over a writing plate which forms a part of a pivoted hand rest table, said feeding

of the paper taking place when a hand resting on the table is lifted therefrom.

It is an important object of this invention to construct a memorandum device of simple 60 and effective construction and adapted to automatically feed one or more sheets of paper over a hand controlled writing plate.

Other and further important objects of this invention will be apparent from the 65 disclosures in the specification and drawings.

The invention (in a preferred form) is illustrated in the drawings and hereinafter more fully described.

On the drawings:

Figure 1 is a top plan view of a memorandum device embodying the principles of this invention.

Fig. 2 is a side elevation thereof.

Fig. 3 is an enlarged central longitudinal section of the device.

Fig. 4 is a transverse sectional view taken on line 4—4 of Fig. 3, showing parts in elevation.

Fig. 5 is a fragmentary sectional view taken on line 5—5 of Fig. 4.

Fig. 6 is a fragmentary side elevation taken on line 6—6 of Fig. 4.

As shown on the drawings:

The memorandum device comprises a base plate or stand 1 having integrally formed thereon a pair of oppositely disposed upright standards or posts 2. Rigidly secured transversely of the base plate and upon the 90 tops of the posts 2, is a U-shaped frame or channel, the arms 3 of which are directed upwardly. A main shaft or axle 4 is provided transversely of the device with the ends rotatably supported on the inner tapered ends of supporting screws 5 which project through the upper ends of the arms 3.

Supported by the screws 5 between the arms 3 is a table comprising side sills 6 and 7 having two adjacent ends connected by a 100 table top or hand rest plate 8. The plate 8 extends from the outer ends of the table sills to within a short distance of a writing board or plate 9, the ends of which are integral with the sills 6 and 7. A slot or opening 105 is provided between the inner edge of the hand rest plate 8 and the front edge of the writing plate 9. The front margin of the writing plate is bent downwardly to form a guide flange 11. The sills 6 and 7 have their 110 rear portions directed downwardly to afford inclined brackets or arms 12, the ends of

which are formed to afford sockets 13 to removably receive the reduced ends of an axle or rod 14 upon which is engaged a rolled web of paper 15, whose inner surface is carbonized. Integrally connecting the sills 6 and 7 at the upper ends of the brackets 12 is a guide strip 16, the front margin of which is bent upwardly to afford a guide flange 17. The rear edge of the guide strip 16 is provided to serve as a knife or blade 18 for cutting off paper. Secured to the sills 6 and 7 and a little below the cutter strip 16 is a guide plate 19.

The sills 6 and 7 are provided with openings 20 for receiving the hooked end of bracket plates 21. Each of the bracket plates 21 is provided with a slot 22 to permit adjustment of the bracket plate when a retaining screw 23 is loosened. Each bracket plate 21 has a plate spring 24 integrally formed thereon with the rear end curled to afford a support for a rotatable transverse auxiliary shaft or axle 25. Rigidly secured on the auxiliary axle 25 are two small secondary friction wheels 26, the peripheral surfaces of which are roughened or knurled and adjustably bear upon the knurled peripheral surfaces of two large main friction wheels 27 secured in place upon the main axle 4.

30 A main power spring 28 has one end adjustably secured to the outer surface of one of the frame arms 3, while the other end is engaged beneath a lug 29 struck outwardly from the table sill 7 as shown in Fig. 2. The main spring 28 acts to normally hold the table 8 in an elevated position.

Each of the sills 6 and 7 is provided with a downwardly directed arm 30, the lower end of which is formed to afford a socket or recess 31. Rotatably and removably seated in the sockets 31 of the arms 30 are the ends of an axle or rod 32, upon which is mounted a rolled web of paper 33. As illustrated in Fig. 3, the paper 15 is guided over the horizontal bar connecting the arms 3, and around the rolled web of paper 33 with the carbonized side of the paper 15 contacting the paper 33. Both of the papers 15 and 33 are led through the table slot 10 over the writing plate 9 and then between the two sets of feed wheels or rollers 26-27. From the feed rollers 26-27 the two sheets of paper 15 and 33 pass between the cutter plate 16 and the plate 19.

55 Rigidly secured to the arm 3 adjacent the sill 6, is one end of a forwardly directed arm 34, the upper edge of which is provided with an integral inwardly directed lug 35, which projects through an opening 36 in the frame sill 6. The front end of the arm 34 has a notch 37 therein for receiving a notched head or flange 38 formed at right angles on the front end of an operating link or bar 39. The bar 39 is deflected intermediate its ends and is pivoted on the outer surface of

the sill 6 by means of a pivot pin 40. The rear end of the pivoted bar 39 has pivotally connected thereto the lower end of a link 41, the upper end of which is pivotally connected by means of a pin to the lower arm 42 of a bell crank 43 pivoted on the main shaft or axle 4. The bell crank 43 comprises a lower arm 42 and an upper arm 44 connected to one another at their inner ends. Secured on the main axle 4 is a ratchet-wheel 45. Pivoted on the inner surface of the frame sill 6 and above the main axle 4 is a gravity-acting detent or pawl 46 disposed in the plane of the ratchet-wheel 45 and adapted to engage with the teeth thereof to permit rotation of the ratchet-wheel and the axle 4 in one direction only, and preventing a reverse rotation. Pivotally mounted on the outer end of the arm 44 of the bell crank 43 is an actuating ratchet or pawl 47. To hold the ratchet 47 in engagement with the teeth of the ratchet-wheel 45, a controlling spring 48 is provided and has one end secured to the arm 44 and the other end engaged with the ratchet 47 as illustrated in Fig. 5.

90 The operation is as follows:

The carbonized paper 15 and the paper 33 pass through the table slot or opening 10 over the writing plate 9, with the carbonized underside of the paper 15 resting upon the upper surface of the paper 33. The double papers pass between the feed rollers 26 and 27 and then pass below the cutter or knife plate 16 out over the plate 19. The upper or auxiliary axle 25 is resiliently supported by the springs 24 to permit papers of different thicknesses to pass between the friction feed rollers. The axle 25 may be adjusted by loosening the screws 23, thereby permitting the bracket plates 21 to be adjusted.

105 The table is normally disposed in an elevated position as shown in full lines in Fig. 3. A person desiring to write a memorandum on the portion of the paper 15 stretched over the writing plate or board 9 simply rests the writing hand upon the table plate 8, the weight of said hand acting to depress the table against the action of the main spring 28, into the dotted line position of Fig. 3. The lug 35 striking against the upper edge of the sill opening 36 limits the downward movement of the table to permit writing upon the paper 15. With the downward movement of the table, the fulcrumed bar 39 is swung on the pivot pin 40, thereby causing the rear end of the bar 39 to move downwardly, pulling the connecting link 41 downwardly therewith. Downward movement of the link 41 acts to swing the bell crank 43 downwardly thereby causing the spring 48 to move the ratchet 47 into engagement beneath one of the teeth of the ratchet-wheel 45.

110 A line of a memorandum may now be 130

- written across the paper 15 and by lifting the hand off of the table plate 8 at the completion of the writing of the line, the stressed main spring 28 acts automatically 5 to return the table to its normal elevated position. The upward movement of the table causes the rear end of the pivoted bar 39 to move upwardly to return the link 41 and the bell crank 43 to normal position. This 10 return to normal position of the bell crank causes the spring controlled ratchet 47 to rotate the ratchet-wheel and the axle 4. Rotation of the axle 4 causes the feed wheels 27 to rotate rearwardly to advance or feed 15 the two sheets of paper 15 and 33 over the writing plate 9 to position a clean portion of the paper over the writing plate to permit the next line of the memorandum to be written. A counter or reverse rotation of 20 the axle 4 and the ratchet-wheel 45 is prevented by the pawl 46, which falls by gravity to engage behind the ratchet-wheel teeth. The roughened or knurled peripheral surfaces of the feed rollers 27 engaging the 25 under surface of the paper 33 cause movement thereof, thereby also causing movement of the paper 15 and rotation of the small rollers 26 which frictionally rest upon the upper surface of the paper 15.
- 30 The operation may thus be repeated until the memorandum is completed. The duplicate sheets of paper may then be cut or severed from the rest of the rolls by simply pulling upwardly thereon to force the same 35 against the cutting edge of the knife 18. The carbonized paper of course permits the making of a carbon copy of the memorandum on the paper 33. If no carbonized copy is desired the paper roll 15 may be omitted 40 and the paper 33 fed across the writing plate 9.
- I am aware that numerous details of construction may be varied through a wide range without departing from the principles 45 of this invention, and I therefore do not purpose limiting the patent granted otherwise than necessitated by the scope of the appended claims.
- I claim as my invention:
- 50 1. In an automatic feed memorandum device the combination with a pivoted writing table, of a frame, a main axle on said frame for supporting said table, feed rollers on said main axle, means for operating the 55 same to cause paper to be fed over the table, brackets adjustably mounted on the sides of the table, springs integrally formed thereon; an auxiliary axle supported by said springs, and auxiliary feed rollers on said 60 auxiliary axle adapted to coat with the main feed rollers to advance paper over the table when the table is released from a depressed position to cause actuation of said operating means.
- 65 2. In an automatic feed device the combination with a supporting frame, a main axle rotatably supported thereon, main feed rollers thereon, a table pivotally supported on said main axle, a main spring having one end adjustably secured to said frame and the 70 other end connected with the table to normally hold the table in an elevated position, springs adjustably supported on said table, an auxiliary axle supported by said springs, auxiliary feed rollers on said auxiliary axle 75 above said main feed rollers, a ratchet-wheel secured on said main axle, and mechanism operable by the table to cause rotation of said ratchet wheel whereby the main axle and the main rollers thereon are rotated to 80 feed paper between said main feed rollers and said auxiliary feed rollers over the table.
3. In a paper feed device of the class described a frame, a main axle supported 85 thereon, feed rollers thereon, auxiliary rollers coacting therewith, a table pivotally mounted on said main axle, a ratchet-wheel secured on said main axle, a gravity acting pawl pivotally supported on said table and engaged with said ratchet-wheel to hold 90 the same against a reverse rotation, a bell crank rotatably mounted on said main axle, a ratchet thereon, a spring for holding the ratchet in engagement with the ratchet-wheel, a link pivotally connected with said 95 bell crank, an arm rigidly secured on said frame, and a bar fulcrumed on said table having one end engaged with said arm and the other end pivotally connected with said link, said table adapted by the resting of 100 a hand thereon to be lowered into a writing position and to set the ratchet to permit the same to actuate said feed rollers to feed paper between the feed rollers and the auxiliary rollers and over the table when the hand is 105 removed from the table and the table is returned to its normal raised position.
4. In a device of the class described, a pivoted writing table, a bell crank, a ratchet mechanism operated thereby, feed means 110 adapted to be actuated by said ratchet mechanism, and means connecting the bell crank with the table and operated thereby for feeding paper over the table.
5. In a paper feed device the combination 115 with a pivoted writing table, of friction feed means, a ratchet mechanism connected with the feed means, a bell crank for operating said ratchet mechanism, and a bar pivotally mounted on the table and connected with 120 said bell crank, said bar mounted to be operated by the table to cause operation of the bell crank and the ratchet mechanism whereby the friction feed means is operated to feed paper over the table.
- 125 6. In a device of the class described, a pivotally mounted spring controlled table normally held in a raised position, paper carrying means supported on the table for supplying paper to be fed over a portion 130

of said table, friction feed members for receiving said paper therebetween, a ratchet mechanism, a bell crank, a ratchet pivoted thereon, a spring connecting said bell crank with said ratchet, a link pivoted on said bell crank, a bar pivoted on said table and having one end pivotally connected with said link, a notched stationary arm, and a notched head on the other end of said pivoted bar engaged with the notched end of said stationary arm.

7. The combination with a writing table, of main feed rollers for feeding paper thereover, bracket plates pivoted on the sides of said table, said bracket plates

having slots therein, screws engaging through said slots and engaging said table to hold the bracket plates in an adjusted position, springs secured to said bracket plates, an axle supported by said springs, and auxiliary feed rollers on said axle for co-action with said main feed rollers to feed paper over the table.

In testimony whereof I have hereunto subscribed my name in the presence of two subscribing witnesses.

EDWARD F. CREEVY.
